2 SHEETS-SHEET 2

UNITED STATES PATENT OFFICE.

HERMAN H. ARN, OF UHRICHSVILLE, OHIO.

RIVET CUTTER.

Application filed April 11, 1922. Serial No. 551,744.

To all whom it may concern:

Be it known that I, HERMAN H. ARN, a citizen of the United States of America, residing at Uhrichsville, in the county of 5 Tuscarawas and State of Ohio, have invented new and useful Improvements in Rivet Cutters, of which the following is a specification.

The object of the invention is to provide 10 a pneumatic rivet cutter or more particularly to provide a rivet cutting attachment for a pneumatic hammer or tool of the pneumatic hammer type, whereby rivets, bolts and the like may be cut without exposing 15 the tool and the operator to the strains and effort which are incident to the use of a chisel and like conventional means of removing rivet heads, and without the risk incident to the conventional methods of 20 forcibly projecting or propelling the detached rivet or bolt heads at the risk of other operatives by the final stroke of the tool; and with these general objects in view the invention consists in a construction and 25 combination of parts of which a preferred embodiment is shown in the accompanying drawings, wherein:—

Figure 1 is a view of a rivet cutting tool embodying the invention.

30 Figures 2 and 3 are sectional views of the same showing the objects respectively in their initial and final positions.

Figure 4 is a section at right angles to the planes of Figures 2 and 4.

35 Figures 5 and 6 are cross sectional views respectively on the planes indicated by the lines 5—5 and 6—6 of Figures 2 and 3.

The apparatus contemplates primarily a 40 pneumatic hammer construction of conventional type including a tubular guide 10 in which operates the hammer piston or plunger 11 and a suitable stock 12 having a grip 13 with which is connected the air inlet nipple 14, said stock being provided interi- 45 orly with any suitable form of means for effecting the usual and well known recipro- catory movement of the hammer or plunger and of which no specific illustration is deemed necessary.

50 Removably mounted upon the guide 10 is a shell 15 having a sleeve 16 to embrace said guide and adjustable to clamp the same and thereby secure the shell in a fixed relation to the guide by means of a bolt 17 or its 55 equivalent, said sleeve being split as indicated to permit of the insertion of the guide

thereinto, and at the extremity of the guide there is arranged a conventional clip 18 for holding a rivet-set shank or follower 19 of special form having a conical or wedge- 60 shaped head 20 for spreading action with relation to jaws 21 which are mounted in the shell and are connected by a pivot 22 having a progressive movement in the shell by reason of the engagement of the terminals 65 thereof with longitudinal guide grooves 23 in the side walls of the shell. The advancement of the pivot pin with relation to the guide grooves is preferably yieldedly induced by means of coiled springs 24 ar- 70 ranged in said grooves around suitable guide pins 25 which extend through perforations in the extremities of the pivot pin, said grooves being provided at their outer ends with stops 26 to limit the advance move- 75 ment of the pin.

The jaws are provided at their inner ends with bevel portions transversely concaved and cooperating to form a conical seat 27 for the conical head 20 of the follower, and the outer ends of the jaws carry preferably 80 removable blades 28 directed toward each other in opposed relation and suitably beveled to extend under and operate jointly in removing the head or swaged end of a 85 rivet such as indicated at 29 employed for example as the means of connection of boiler plates shown at 30 in Figure 2. The blades may be secured in place by suitable screws 31 to permit of their replacement or removal 90 for sharpening or grinding.

With the parts in the positions indicated in Figure 2 and the jaws extended beyond the contracted outlet end 32 of the shell and the jaws in spanning relation with the rivet 95 to be cut as in Figure 2, the impact of the hammer against the inner end of the follower tends by reason of the cooperating conical head of said follower with the seat of the inner ends of the jaws to spread the 100 latter and thereby force the bladed extremities of the jaws toward each other, and as pressure is applied to the pneumatic tool in the ordinary way to hold the jaws to their work, the closing movement of the bladed 105 ends of the jaws will be accompanied by an advance movement of the hammer and the shell 15 with relation to the jaws to the final position indicated in Figure 3. The advance movement of the shell obviously is 110 accompanied by a spreading of the inner ends of the jaw members for the accommoda-

tion of which the shell is enlarged laterally as shown at 33. It will be obvious moreover that the advance movement of the shell with relation to the jaws is accompanied by 5 the compression of the springs 24, and when the tool is removed from the severed rivet the jaws are advanced with relation to the shell to resume the relative position indicated in Figure 2 and with the operative 10 ends of the jaws spread in preparation for application to a succeeding rivet.

As the operation of the jaws serves to cut the rivet quickly from opposite sides, it will be obvious that when the rivet head or swage 15 is detached it is not subject to propulsion violently or forcibly as when a cutting tool such as a chisel pneumatically or manually driven is used as the cutting tool and operates continuously in one direction and from 20 one side of the rivet. It has been found in practice that this forcible propulsion of the rivet head is liable to cause injury to other workmen engaged in the vicinity of the operator of the rivet cutting tool and under 25 some conditions to the rivet cutter.

Having described the invention, what is claimed as new and useful is:—

1. A tool for the purpose described having in combination with a pneumatically driven hammer, a terminally tapered follower pin 30 for actuation by the hammer and pivotally connected jaws provided at their outer ends with opposed cutting blades and at their inner ends with a tapered seat for engagement by the follower pin, said jaws being mounted for joint longitudinal movement towards said follower pin.

2. A tool for the purpose described having in combination with a pneumatically driven 40 hammer, a terminally tapered follower pin for actuation by the hammer and pivotally connected jaws provided at their outer ends with opposed cutting blades and at their inner ends with a tapered seat for engagement by the follower pin, and a jaw guiding shell carried by the hammer stock and having guides for directing the joint longitudinal movement of the jaws towards said follower pin.

3. A tool for the purpose described having in combination with a pneumatically driven hammer, a terminally tapered follower pin 45 for actuation by the hammer and pivotally connected jaws provided at their outer ends with opposed cutting blades and at their inner ends with a tapered seat for engage-

ment by the follower pin, and a shell carried by the hammer stock and embracing the inner ends of said jaws, the walls of the shell being provided with guide grooves for the 60 reception of the terminals of the jaw connecting pivot.

4. A tool for the purpose described having in combination with a pneumatically driven hammer, a terminally tapered follower pin 65 for actuation by the hammer and pivotally connected jaws provided at their outer ends with opposed cutting blades and at their inner ends with a tapered seat for engagement by the follower pin, and a shell carried 70 by the hammer stock and embracing the inner ends of said jaws, the walls of the shell being provided with guide grooves for the reception of the terminals of the jaw connecting pivot, and springs being disposed to 75 yieldingly resist the inward movement of the jaws with relation to the shell.

5. A tool for the purpose described having in combination with a pneumatically driven hammer, a terminally tapered follower pin 80 for actuation by the hammer and pivotally connected jaws provided at their outer ends with opposed cutting blades and at their inner ends with a tapered seat for engagement by the follower pin, and a shell provided with means for detachable engagement with the stock of the hammer and having longitudinal guide grooves for the reception of the extremities of the jaw connecting pivot.

6. A rivet cutting tool having, in combination with a pneumatic hammer provided with a tool guide, a follower pin provided with a tapered head, a shell provided with means for detachable engagement with the hammer stock and extending in advance of and embracing the head of the follower pin, pivotally connected jaws disposed within the shell with their inner ends provided with complementary seat members for the reception of the tapered head of the follower pin, said shell being provided with opposite longitudinal guide grooves for the reception and guidance of the extremities of the jaw connecting pivot pin, and springs arranged 100 in operative relation with the said pivot pin for yieldingly advancing the jaws with relation to the shell.

In testimony whereof he affixes his signature.

HERMAN H. ARN.
